COMBINATION DISHWASHING BRUSH AND SCRAPER

Joseph Vallis, Toronto, Ontario, Canada, assignor to
Valden Company, Toronto, Ontario, Canada

Filed Mar. 19, 1962, Ser. No. 69,334

Term of patent 14 years

(Cl. D9—2)

FIG. 1 is a side elevational view of a combination dishwashing brush and scraper showing my new design;

FIG. 2 is a top plan view thereof;

FIG. 3 is a bottom plan view thereof;

FIG. 4 is an elevational view of the left end thereof;

FIG. 5 is a top view thereof taken slightly in perspective; and

FIG. 6 is an elevational view of the right end thereof.

The undisclosed side of the dishwashing brush is a mirror image of the side shown.

The characteristic features of my design for the combination dishwashing brush and scraper disclosed reside in the specific integral brush back, scraper and handle as shown.

I claim:

The ornamental design for a combination dishwashing brush and scraper, as shown and described.
